(57) **CLAIM**

The ornamental design for a fork grilling utensil, as shown and described.

DESCRIPTION

FIG. 1 is a top view of the fork grilling utensil.

FIG. 2 is a front view of the fork grilling utensil.

FIG. 3 is a profile side view of the fork grilling utensil; and,

FIG. 4 is a bottom view of the fork grilling utensil.

The broken lines are for illustrative purposes only and form

no part of the claimed design.
